CIRCUIT FOR TELEVISION PICTURE TUBES

Adrianus Johannes Wilhelmus Marie van Overbeek, Eindhoven, Netherlands, assignor to Hartford National Bank and Trust Company, Hartford, Conn., as trustee

Application April 1, 1953, Serial No. 346,083

Claims priority, application Netherlands April 10, 1952

5 Claims. (Cl. 315—21)

This invention relates to a circuit for a television picture tube of which the screen is composed of three strips of the same width which are cyclically repeated and which reproduce the fundamental colours, which screen is scanned in two directions substantially at right angles to one another, one direction coinciding with the direction of length of the strips.

In known circuits of the above-mentioned kind the picture tube serves solely for the reproduction of colour television images. Maximum anastigmatism of the cathode-ray beam of the tube is obtained in such manner that the cross-section of the beam at the area of the screen scans one colour strip at the same time, so that one colour only is reproduced.

The deflection of the beam is chosen, for example, to be such that at first all strips of one colour, subsequently all strips of the second colour and then all strips of the third colour are scanned. It is alternatively possible for the strips to be scanned in succession, in which event, for example, a red strip, then a green strip, subsequently a blue strip and then again a red strip, etc. are scanned.

The object of the circuit according to the invention is to make the picture tube serviceable not only for reproducing colour images, but also for the reproduction of black-white images and, furthermore, for another method of reproducing colour television images which is suitable for a colour television system in which information is transmitted about brightness, colour and degree of saturation of the image to be reproduced.

The circuit according to the invention is characterised in that the cathode-ray beam exhibits astigmatism, the largest dimension of the cross-section of the beam at the area of the screen being substantially equal to three times the width of a strip and the smallest dimension of the cross-section at the same area being substantially equal to the width of one strip, provision being made of means for varying the orientation and the dimensions of the cross-section of the beam with respect to the direction of length of the strips.

In order that the invention may be readily carried into effect, it will now be described with reference to the accompanying drawing showing, by way of example, one embodiment thereof.

Fig. 1 shows a plurality of strips of the screen, some forms of the cross-section of the beam at the area of the screen being shown, which is also the case in Fig. 2.

Fig. 3 shows a picture tube comprising a screen such as shown in Fig. 1 or Fig. 2, some control means of the tube being shown diagrammatically.

Fig. 4 is a sectional view at the area of the dotted line IV—IV in Fig. 3, Fig. 5 showing diagrammatically a circuit of a deflection coil and the supply circuits used therewith.

The part of the screen 1 shown in Fig. 1 is constituted by groups of three strips 2, 3, 4 and 5, 6, 7, which are cyclically repeated and which reproduce the fundamental colours, for example red (r), green (g) and blue (b).

Reference numeral 8 indicates one obtainable cross-

2

section of the cathode-ray beam where it strikes the screen, the main dimension of which lies in the direction of length of the blue strip 4. The smallest dimension of the cross-section of the beam is at the most equal to the width of the strip.

If the beam with this orientation of its cross-section is deflected in the direction of length of the strip, a visible blue signal is reproduced.

When the beam is moved through a distance equal to 10 the width of one strip in the vertical direction, for example upwards, the cross-section of the beam lies on a green strip and a visible green signal is reproduced upon horizontal deflection.

With this orientation of the cross-section of the beam 15 the picture tube is thus suitable for reproducing a colour television image, it being mentioned for the sake of completeness that the resolving power in the horizontal direction is smaller than with the conventional scanning method, in which the dimension of the cross-section of 20 the beam in the horizontal direction is substantially equal to that in the vertical direction.

Since the beam is astigmatic, it is possible by varying 25 the focal length of the electron-optical system of the tube to obtain also an orientation of the cross-section of the beam at the area of the screen by which the largest dimension of the cross-section is directed vertically, as indicated at 9. In this case, the beam strikes the strips 3 (g), 4 (b) and 5 (r) simultaneously, so that a black-white signal is now reproduced by the tube.

30 If the beam is moved in the vertical direction, it is possible for the whole screen to be scanned.

If the vertical position of the beam, after one strip 35 has been scanned, varies only over the width of one strip or two strips, this also results in subsequent horizontal scannings partly overlapping, so that the structure of the strips is rendered substantially invisible.

Fig. 2 shows three forms 10, 11, 12 of the cross-section of the beam in which the center of the beam is 40 centered on the green strip 13, and furthermore three forms 14, 15, 16, in which the center of the beam is centered on the blue strip 17.

At the position 10, white instead of green is reproduced, since red, green and blue strips are struck by the beam. Consequently, the degree of saturation of the 45 green is nil, since the reproduced "colour" is located at the white point of the colour triangle.

At the position 12, green only is reproduced, the saturation of the green signal thus being equal to 1.

If, starting from the position 10, the focal length of 50 the electron-optical system is gradually varied until the position 12 is reached, a plurality of intermediate forms of the cross-section of the beam occur at the area of the screen, one of which is indicated at 11.

At the position 11, the beam strikes the strip 13, but 55 at the same time it also strikes part of the red strip located above and the blue strip located below, which corresponds to a degree of saturation of the green which is comprised between 0 and 1 and which is, for example, 0.5.

Consequently, if at a determined position on the screen the focal length of the electron beam system is 60 varied thereby changing the size of the electron beam in the vertical direction from the center of the cross-section of the beam, this causes the degree of saturation of the reproduced colour to be varied.

If the deflection is varied in the vertical direction, so that the center of the cross-section of the beam lies, for example, on the blue strip 17, blue can be reproduced 65 with differing degrees of saturation, the positions 14, 15, 16 exhibiting, for example, the degrees of saturation 0, 0.5 and 1.

In producing a white color by means of the vertically

elongated electron-beam spot 10, as described above, there will be a slight predominance of green color due to the greater spot area on the green color strip. Similarly, the spot 14 will produce a slight predominance of blue color, and the spot on the next line will produce a slight predominance of red color. These slight deviations from pure white are scarcely noticeable, due to the wide color tolerance of the human eye. The effect of pure white is produced, however, due to integration by the eye of the slightly predominating colors of green, blue and red during successive scannings of the color strips.

Consequently, if a colour television signal is supplied to a colour television receiver and this signal comprises the required information: brightness, colour and degree of saturation, this signal may be reproduced with the use of a circuit according to the invention.

One embodiment suitable for this purpose is shown diagrammatically in Fig. 3.

A cathode-ray tube 18 comprises a screen 19 having strips of the kind shown in Fig. 1 or Fig. 2.

Furthermore, the tube comprises a cathode 20, a Wehnelt-electrode 21 and a first anode 22, by which a cathode-ray beam is generated in known manner with the use of suitable biasing potentials.

The beam is focussed with the use of a focussing coil 23 of known construction. As viewed in the direction of movement of the electrons of the beam, a coil 24 fed with suitable direct-current is provided behind the focusing coil 23. A cross-section of coil 24 taken along the dotted line IV-IV is shown in Fig. 4, reference numeral 25 indicating the wall of the tube 18 at the area IV-IV.

As may be seen from Fig. 4, the coil 24 has a shape which is flattened and, as the case may be, for example elliptic. The cathode-ray beam thus acquires the required astigmatism, and the cross-section shape of the beam along a portion of the length thereof in the vicinity of the screen varies from an oval shape with the longest diameter perpendicular to the screen strips, to an oval shape with the longest diameter parallel to the screen strips. By varying the focus current in the focus coil 23, these differently shaped cross-section areas of the beam will shift along the length of the beam, and thus the beam can be caused to have the desired cross-section at the point where it strikes the screen.

The astigmatism of the cathode-ray beam may alternatively be ensured in a different way, as is well-known in the aim at avoiding this phenomenon which, as a rule, is undesirable.

Thus, for example, in the case of the deflection coils, which are not shown in Fig. 3, it is possible for the two halves of one deflection coil to be supplied in opposite senses with direct current, such as shown diagrammatically in Fig. 5.

The deflection coil is in this case constituted by halves 26 and 27. The deflection current is supplied between earth and a terminal 28 via a capacitor 29 to the halves of the coil. The latter are connected in series in opposite senses, the series-connection including a battery 30.

A further method of obtaining astigmatism is to provide the cathode-ray tube with an electron-optical system comprising a cylindrical electrode of elliptical section.

Furthermore, for example, when using a cathode-ray tube in which use is made of electrostatic deflection, the mean voltage of a set of deflection plates may be different from the voltage of the second anode of this tube.

Referring again to Fig. 3, it is mentioned that a third coil 31 is provided around the neck of the tube. This coil serves to deflect the cathode-ray beam in the vertical direction and in this case through a distance equal at most to twice the width of the strips.

In the circuit shown in Fig. 3, the Wehnelt electrode 21 controls the intensity of the electron beam and has supplied to it, at 32, a voltage comprising in formation

about the brightness of the colour television signal received.

Information about the degree of saturation is supplied to the focussing coil 23 at 33, information about the colour being applied to a deflection coil 31 at 34.

The normal deflection of the beam in the horizontal and vertical directions is brought about in known manner. For the sake of completeness, it is mentioned that the information about colour need not necessarily be supplied to a particular deflection coil 31, but may alternatively be superposed on the saw-tooth oscillation supplied to the ordinary vertical deflection means.

Under control of the colour information supplied to the coil 31, it is thus determined whether the center 15 of the beam must fall, for example, on strip 13 or on strip 17 of Fig. 2.

The information about degree of saturation supplied to the focussing coil 23 determines the orientation of the cross-section of the beam in accordance with the positions 20 10 and 12 of Fig. 2 and the intermediate transition shapes such, for example, as 11.

The brightness signal supplied to the Wehnelt electrode 21 determines the strength of the cathode-ray beam and hence the brightness of screen 19 of the tube.

25 For the sake of completeness, it is to be noted that the correcting means usually employed in the known circuits may also be used in the circuit according to the invention. If it should appear, for example, that variation in the current strength of the cathode-ray beam results in variation 30 of the focal length, which would also cause variation in the shape of the cross-section of the beam, a signal derived from the brightness signal may be supplied as a correcting voltage to the focussing coil 23, so that the focussing is not affected by the brightness.

35 What I claim is:

1. A color television display system comprising a picture tube containing a screen composed of cyclically repeated parallel groups of equal-width strips of materials which produce different colors when struck by an electron beam, means for producing an electron beam directed toward said screen, means for causing said beam to scan said screen in a direction parallel to said strips and in a direction perpendicular to said strips, and means for selectively causing variable astigmatism of said beam by such an amount that at said screen the dimension of the cross-section of the beam in a direction perpendicular to the length of said strips is selectively varied between the limits of substantially the width of a group of said strips and the width of a single strip.

40 2. A system as claimed in claim 1, in which said means for causing variable astigmatism of the electron beam comprises a beam-shaping means for causing the beam to have an oval-shaped cross-section and means for focusing said beam whereby the cross-section shape of

55 the beam along a portion of the length thereof in the vicinity of said screen varies from an oval shape with the longest diameter perpendicular to said screen strips, to an oval shape with the longest diameter parallel to said screen strips, and means for varying the focus of said electron beam to selectively focus the beam on said screen at various points along said portion of the length thereof.

60 3. A system as claimed in claim 2, in which said beam-shaping means comprises a coil having an oval-shaped cross-section and positioned to surround said electron beam.

65 4. A system as claimed in claim 2, in which said means for causing said electron beam to scan said screen comprises a pair of magnetic deflection coils arranged to produce a magnetic deflection field perpendicular to said beam, and in which said beam-shaping means comprises means for applying direct current to the coils of said pair in opposite sense.

70 5. A color television display system comprising a picture tube containing a screen composed of cyclically re-

peated parallel groups of equal-width strips of materials which produce different colors when struck by an electron beam, means for producing an electron beam directed toward said screen, means for causing said beam to scan said screen in a direction parallel to said strips and in a direction perpendicular to said strips, means for causing said electron beam to have elliptical astigmatism whereby the cross-section of said beam along a portion of the length thereof in the vicinity of said screen varies from an oval shape with the longest diameter perpendicular to said screen strips, to an oval shape with the longest diameter parallel to said screen strips, said longest diameter being substantially equal to the total width of a group of said screen strips, means adapted to control the focus of said electron beam in response to color saturation signals, means adapted to control the intensity of said electron beam in response to brightness signals, and means for selectively deflecting said electron beam in a

5

10

15

direction perpendicular to said strips and by a maximum amount equal to the width of a group of said strips in response to color signals.
